DESIGN FOR A DOLL

Izetta Stokes, Belmont, Calif.

Application September 18, 1946, Serial No. 133,384

Term of patent 7 years

(Cl. D34—4)

To all whom it may concern:

Be it known that I, Izetta Stokes, a citizen of the United States of America, residing at Belmont, in the county of San Mateo and State of California, have invented a new, original, and ornamental Design for a Doll, of which the following is a specification, reference being made to the accompanying drawing, forming a part thereof:

Fig. 1 is a front elevation of the doll showing my new design.

Fig. 2 is a side elevation of the doll.

I claim:

The ornamental design for a doll, substantially as shown.

IZETTA STOKES.
